UNITED STATES PATENT OFFICE

CHARLES R. DRAKE, OF ROCHESTER, NEW YORK, ASSIGNOR TO THE LINE-A-TIME MFG. CO. INC., OF ROCHESTER, NEW YORK, A CORPORATION OF NEW YORK

COPYHOLDER

Application filed April 2, 1927. Serial No. 180,482.

This invention relates to copyholders of the type in which a copy plate and a line indicator spanning the copy plate are mounted on a vertically extending casing plate or frame and are moved relatively to each other by mechanical means, and in which the casing plate or frame has a supporting arm pivotally attached thereto for movement from an inoperative position in which it extends substantially parallel with the copy plate to an operative position in which it extends forwardly of and substantially perpendicular to the front face of the copy plate.

An object of this invention is to provide improved supporting means for a copyholder. Another object is to provide improved means for mounting the casing plate or frame. Another object is to provide an improved supporting arm structure. Another object is to provide improved means for locking the supporting arm in its operative position. Another object is to provide improved means for attaching a copyholder to a desk or table or other support. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of this invention,

Figure 1 is a side elevation of the assembled copyholder;

Figure 2 is a front elevation of the copyholder with the copy plate removed;

Figure 3 is a fragmentary rear elevation showing the bottom portion of the casing plate and the supporting means therefor;

Figure 4 is a sectional plan view of the copyholder with the copy plate removed, and showing the supporting arm in its operative or extended position;

Figure 5 is a view similar to Figure 4, but showing the supporting arm in its inoperative or folded position;

Figure 6 is a fragmentary end elevation showing the means for attaching the supporting arm to the frame and the means for locking the supporting arm in its extended position;

Figure 7 is a sectional elevation taken substantially on line 7—7 of Figure 4;

Figure 8 is a sectional elevation taken substantially on line 8—8 of Figure 4;

Figure 9 is a sectional elevation taken substantially on line 9—9 of Figure 1;

Figure 10 is a fragmentary sectional elevation taken substantially on line 10—10 of Figure 3, and showing the supporting means for the casing plate or frame;

Figure 11 is a fragmentary elevation partly in section, taken substantially on line 11—11 of Figure 4;

Figure 12 is a perspective of the base or supporting means for the casing plate;

Figure 13 is a perspective view of one side wall of the supporting arm showing the connecting flanges and hinge members formed integrally therewith; and

Figure 14 is a perspective view of the other wall of the supporting arm.

Similar reference characters refer to similar parts throughout the several views of the drawings.

Referring now to Figure 1 of the drawings, there is shown a copyholder comprising the usual casing plate or frame 20, copy plate 21, line indicator 22, and paper holding clip 23. The copyholder is provided with the usual actuating mechanism (not shown) which is controlled by an operating lever 24 pivotally mounted on an improved supporting arm 25.

The casing plate 20 has its bottom flange spot welded, as indicated at 26 in Figures 4 and 5, to a base plate 27 which projects beyond the opposite side edges of the said casing plate. A combination angle bar and Z-bar 30 is mounted on the rear portion of the base plate 27 with one of its legs or flanges engaging the upper face of the said base plate and spot welded thereto as indicated at 31 in Figures 4 and 5. The other leg or flange of the angle bar portion of the member 30 extends substantially vertically and engages

55

60

65

70

and is spot welded to the rear face of the casting plate 20 as indicated at 32 in Figures 2 and 10. One end of the angle bar portion of the member 30 has an integral flange 33 formed thereon which projects forwardly and is spot welded to a side flange of the casing plate. The angle bar portion merges into the Z-bar portion at its other end and the vertical leg or flange of the said angle bar forms 10 the web of the Z-bar.

The upper flange 34 of the Z-bar projects substantially horizontally forwardly in parallel relation to the upper surface of the front portion of the base plate 27, and its inner end 15 has a vertical flange 35, formed integrally therewith, which engages and is spot welded to a side flange of the casing plate. The flange 34 and base plate 27 form a channel or housing for an end of the supporting arm. 20 A channel-shaped guide member 36 is mounted between the flange 34 and base plate 27 with its web spot welded to the web of the Z-bar and its legs or flanges 37 projecting forwardly in spaced relation to the flange 34 25 and base plate 27.

The supporting arm 25 comprises vertical side walls 40 and 41. Side wall 40 has upper walls 42 and 43 and a bottom wall 44 formed integrally therewith. The upper wall 43 30 merges into an end wall 45, and the end portions of the upper wall 42 and bottom wall 44 are extended to form spaced hinge members 46 and 47 projecting at right angles to the side wall 40. The end edges of the hinge 35 members 46 and 47 are substantially parallel and they merge with and extend perpendicularly to the adjacent end edge of the wall 40. The hinge members 46 and 47 are pressed inwardly to form recesses or grooves 50 and 51 40 which have concentric openings or bores in their bottom walls.

The side wall 41 has tabs or flanges 52 formed thereon adjacent its lower edge and projecting substantially at right angles thereto. The flanges 52 are provided with downwardly struck integral tongues 53 which are adapted to project into slots 54 in the bottom wall 44 to aid in holding the side wall 41 in its proper position relatively to the side 50 wall 40. The upper central portions of the side walls 40 and 41 are extended upwardly to form tabs 55 and 56 which are provided with slots or bores which are concentric when the supporting arm is assembled. A bolt or 55 pin 57 extends through the apertures in the members 55 and 56 and through an aperture in the operating lever 24 and forms a pivot for the said operating lever while functioning to hold the side walls 40 and 41 in their 60 proper relative positions to provide a suitable support.

The bottom wall 44 and end wall 45, at their juncture, are provided with open end slots. The slot in the end wall 45 is slightly 65 larger than the slot in the bottom wall, in

order that the head of an ordinary nail or screw projecting above a horizontal surface when its shank fits closely between the walls of the slot in the member 44, may pass through the said slot and the arm may thus be locked against vertical movement. In order to lock the arm against horizontal movement, a U-shaped latch member 60 has its side arms pivotally mounted on a horizontally extending pin 61 mounted on the side walls 40 and 41. The web or bottom of the U-shaped member 60 is adapted to cover the slot in the end wall 45 when in its lower-most position (Figure 8).

A spring plunger, comprising part of the means for locking the supporting arm in its extended position, is mounted on the hinge members 46 and 47, and comprises a pin member 62 and a helical spring 63. The pin 62 is so mounted that its upper end portion is seated for sliding movement in the aperture formed in the recess 50 and its lower end portion is seated for sliding movement in the aperture formed in the recess 51. The upper end surface of the pin 62 is normally flush with the outer surface of the recess 50 and the lower end portion is tapered and normally projects below the outer surface of the recess 51. A second pin 64 extends transversely through the pin 62 and its end portions support a washer 65 which forms a seat for an end of the spring 63. The other end of the spring 63 bears against the inner wall of the recessed portion of the hinge member 46. The pin 64 also serves to limit the downward movement of the pin 62.

When the supporting arm is applied to the copyholder, the hinge member 46 is inserted between the flange 34 and a flange 37 and the hinge member 47 is inserted between the other flange 37 and the base plate 27, and a pin 65' extends through apertures in the said flanges and hinge members and forms a pivot about which the supporting arm may be rotated. The pin 65' is so positioned that when the supporting arm extends substantially perpendicular to the copy plate, the end edges of the hinge members and the side wall 40 engage the inner surface of the Z-bar web.

A button 66 having a recessed, beveled head is mounted on the base plate 27 with its head projecting above the upper surface thereof. The button 66 is positioned adjacent the web of the Z-bar in the path of travel of the spring plunger. As the supporting arm moves outwardly, the spring plunger moves inwardly and the tapered end of the pin 62 engages the beveled surface of the member 66 and moves upwardly thereon against the action of the spring 63. When the end edges of the hinge members engage the web of the Z-bar, the center of the recess in the member 66 and the axis of the pin 62 coincide and the spring 63 moves the tapered end of the pin into the said recess, thereby locking the arm in posi-

tion. Since the end of the pin 62 is tapered, pressure applied on the supporting arm in the opposite direction will cause the said pin to ride up the inner surface of the recess and the arm may thus be released. The recesses 50 and 51 provide clearance between the ends of the pin 62 and the flange 34 and base plate 27 during the movement of the said pin with the supporting arm. The lower surface of the 10 outer end portion of the bottom wall 44 of the supporting arm lies substantially in the same horizontal plane as the lower surface of the base plate 27.

Most of the various parts of the apparatus 15 are preferably formed of pressed steel which adapts itself readily to spot welding.

From the foregoing it will be seen that there is herein provided an apparatus which embodies the features of this invention and 20 achieves the objects thereof. An improved copyholder structure has been provided which is thoroughly efficient and dependable in use, of strong and durable construction, and relatively simple and inexpensive to manufacture.

25 As many embodiments may be made in the above invention and as many changes might be made in the embodiment above set forth, it is to be understood that all matter herein-before set forth or shown in the accompanying drawings is to be interpreted as illustrative and not in a limiting sense.

I claim as my invention:

1. In a copyholder, a base plate, a casing plate rigidly mounted on said base plate, and 35 a brace comprising a base portion and an angularly extending flange portion mounted on said base plate with said flange portion engaging said casing plate.

2. In a copyholder, a base plate, a casing plate thereon, an angle iron brace having its respective flanges engaging said base plate and said copy plate, and means for securing all of said parts in assembled relation.

3. In a copyholder, a base plate, a casing plate rigidly mounted on said base plate, and 45 a brace mounted on said base plate with its body portion engaging the back of said casing plate and having side arms engaging the sides of said casing plate.

50 4. In a copyholder, a base plate having a casing plate mounted thereon, an angle bar mounted on said base plate with one leg engaging the rear face of said casing plate, a forwardly projecting supporting arm formed on one end of said angle bar and engaging a 55 side of said casing plate, and a forwardly projecting flange formed on the opposite end of said angle bar and engaging the opposite side of said casing plate to provide supporting 60 means therefor.

5. In a copyholder, a base plate, a casing plate mounted on said base plate, an angle bar mounted on said base plate with one leg engaging the rear face of said casing plate, a 65 forwardly projecting flange formed integral-

ly with said angle bar adjacent an end thereof and forming with said base plate a channel, and a copyholder supporting arm having an end portion pivotally mounted within the channel thus formed.

6. In a copyholder, a base plate, an angle bar mounted on said base plate, a flange formed integrally with a leg of said angle bar and extending over a portion of said base plate in spaced relation thereto, a pivot pin 70 extending between said flange and said base plate, and a copyholder supporting arm mounted on said pivot pin.

7. In a copyholder, a base plate, a Z-bar mounted on said base plate adjacent an end thereof with one of its flanges extending over a portion of said base plate in spaced relation thereto, a pivot pin extending between said flange and said base plate, and a copyholder supporting arm mounted on said pivot 75 pin.

8. In a copyholder, a base plate, a flange member rigidly mounted on said base plate in spaced relation thereto, a pivot member extending between said base plate and said flange, and a supporting arm mounted on said pivot member.

9. In a copyholder, a base plate, a flange member rigidly mounted on said base plate in spaced relation thereto, spaced guide flanges 90 rigidly mounted between said flange member and said base plate, a pivot member mounted on said flange member and said base plate and extending through said guide flanges, and a supporting arm provided with 95 spaced flanges mounted on said pivot member with one of said spaced flanges extending between said flange member and a guide flange and another spaced flange extending between another guide flange and the base plate.

10. In a copyholder, a base member, a supporting member pivotally mounted on said base member, a spring plunger mounted on one of said members parallel to the axis of the pivot, the other member being provided with a recess for the reception of an end of said spring plunger to lock said members against relative movement.

11. In a copyholder, a base provided with a recess, a supporting arm pivotally mounted on said base adjacent the recess therein, and a spring plunger mounted on said supporting arm and having an end portion adapted to project through an opening in said arm and enter said recess to lock said arm against pivotal movement.

12. In a copyholder, a base, a supporting arm pivotally mounted on said base, a spring plunger mounted on said supporting arm and movable therewith, said plunger having a tapered end portion projecting beyond an outer surface of said arm, and a beveled detent mounted on said base in the path of travel of said tapered end portion.

13. In a copyholder, a base, a supporting arm pivotally mounted on said base, a stop member mounted on said base for limiting the movement of said supporting arm in one direction, a spring plunger mounted on said supporting arm for movement therewith, said plunger having a tapered end portion projecting beyond an outer surface of said supporting arm, and a detent having a beveled side surface and a recess formed in its top surface mounted on said base in the path of travel of the tapered end portion of said plunger, said tapered end portion being adapted to ride over the beveled surface of said detent as the supporting arm is moved toward the stop member and to be seated in the recess formed in said detent when the supporting arm engages the stop member.

14. In a copyholder, a supporting arm comprising spaced side walls, top and bottom walls extending between said side walls, and a hinge member formed integrally with one of said side walls.

15. In a copyholder, a supporting arm comprising spaced vertical side walls, top and bottom walls extending between said side walls, and a pair of vertical supporting members formed integrally with and extending above said side walls.

16. In a copyholder, a supporting arm comprising spaced side walls, an end wall provided with an open end slot extending between said side walls, a bottom wall provided with an open end slot extending between said side walls with its slotted end adjacent the slotted end of said end wall, and a latch member pivotally mounted on said side walls and having a portion which is adapted for contact with said end wall to cover the slot therein.

17. In a copyholder, a casing plate having a marginal flange extending laterally from the bottom and side edges thereof, a base plate supporting said casing plate and having said flange engaged therewith, a bar member engaged with said base member adjacent said casing plate having a lateral flange engaged with said casing plate, and means for securing said bar member, base plate and casing plate in assembled relation.

18. In a copyholder, a casing plate having a marginal flange extending laterally from the bottom and side edges thereof, a base plate supporting said casing plate and having the flange at the bottom engaging therewith, a bar member engaged with said base member adjacent said casing plate having a lateral flange engaged with said casing plate, said bar member and base plate extending beyond the ends of said casing plate and having spaced parallel flanges on one of said ends, and means securing said base plate, casing plate and bar member in assembled relation.

19. In a copyholder, a side arm comprising a pair of plate members, one of said members

having laterally extending flanges on the upper and lower edges engaging the corresponding edges of the other member, each of said members having interfitting parts at the lower edges for retaining said members in spaced parallel relation, each member having spaced upwardly extending tabs on the upper edges, an operating lever positioned between the tabs and means extending through the tabs and the operating lever pivotally mounting the operating lever on the side arm and securing said side plates in assembled relation in co-operation with the parts at the bottom edges thereof.

20. In a copyholder, a casing member, a copyplate and line indicator mounted for relative movement on said casing member, a side arm, means connecting the side arm and the casing member, a headed stud mounted on a support for the copyholder, and means on said side arm having detachable inter-locking connection with said stud for anchoring said copyholder to said support.
